VENDING MACHINE

John W. Starr and Carradine B. Elliott, Kansas City, Mo., assignors to The Cigavend Corporation, Kansas City, Mo.

Application February 2, 1933, Serial No. 654,962

18 Claims. (Cl. 312—83)

This invention relates to improvements in vending machines, and more especially to a novel machine for use in vending slender articles such as cigarettes.

5 One of the objects of the invention is to provide a cigarette vending machine designed to vend cigarettes directly from the original packages, and the machine is constructed particularly to vend cigarettes from the conventional flat tin boxes which hold fifty cigarettes arranged in rows side by side.

Another object of the invention is to furnish a cigarette vending machine which will comply with the Federal laws, both with regard to exhibiting the broken seal or stamp, and also displaying the usual notice which is impressed on the packages.

A further object is to supply a vending machine designed to operate on the cigarettes in a plurality of packages, the mechanism being such that the cigarettes are vended successively from the rows within one box and then successively from the rows in a second box.

A still further object is to provide a cigarette vending machine controlled by coin operated mechanism so that a single cigarette may be sold for one cent.

With the foregoing objects outlined and with other objects in view which will appear as the description proceeds, the invention consists in the novel features hereinafter described in detail, illustrated in the accompanying drawings, and more particularly pointed out in the appended claims.

35 Referring to the drawings.

Fig. 1 is a perspective view of our improved machine.

Fig. 2 is a longitudinal vertical sectional view of the same, taken on the line 2—2 of Fig. 1.

40 Fig. 3 is a transverse vertical sectional view taken on the line 3—3 of Fig. 2.

Fig. 4 is a view partly in elevation and partly in section, taken on the line 4—4 of Fig. 2.

Fig. 5 is a longitudinal horizontal sectional view taken on the line 5—5 of Fig. 2.

45 Fig. 6 is a view similar to Fig. 3, but partly in elevation, and showing particular positions of parts of the mechanism at the time when a dump plate is open.

50 Fig. 7 is a sectional view of a detail, taken on the line 7—7 of Fig. 2.

In the drawings, 8 designates a base which supports a removable cover or case 9.

55 Side plates or supporting walls 10 are rigidly mounted on the base and arranged within the

case, and these walls carry spaced supporting bars 11 and 12 which extend lengthwise of the case and are adapted to support a plurality of cigarette boxes or magazines 13 arranged in inclined position, side by side, as best shown in Fig. 1. These boxes are made of tin and each is designed to hold fifty cigarettes 14, twenty-five of these cigarettes being positioned at one side of the package, and twenty-five at the other side.

Before the cigarette packages are placed in the machine, an inclined guide member 15 is slipped into the front portion of each package beneath the usual paper sheet 16 which surrounds the cigarettes, and when the package is placed in the machine, the front end 17 of this paper sheet is folded over the front end of the box, and the latter is placed on the spaced supporting bars 11 and 12, as best shown in Fig. 3.

It will be noted that each box has a hinged cover 17a, and a glass closed window 18 in the top of the case permits the covers, as well as the stamps on the front end of the same to be seen. Furthermore, as the bars 11 and 12 are spaced, a window 19 in the back of the case permits the usual notice on the bottom of the box to be read by means of a mirror 20 which is placed in an inclined position beneath the box supports.

A cross rod 21 functions as a support for the paper sheets of the boxes, and the rod is supported by plates 22 which are vertically arranged and secured to the walls 10, and each of these plates is provided with a V-shaped slot 23, which slots function as guides for a rod 24 on which are hinged followers 25. Each of the boxes is supported in an inclined position to facilitate feeding cigarettes from the same, and it will be noted that the guide 15 cooperates with the bottom of the box to form a substantially V-shaped surface which is substantially parallel to the slots 23. These followers, as best shown in Fig. 5, are provided with medial notches 26 to accommodate the arms 27 of vertically disposed dividers which are adapted to rest in the cigarette boxes and to divide the layers of cigarettes at one side of the package from the layers of cigarettes at the other side of the package.

Each divider is pivotally mounted on a shaft 28, so that the dividers may be swung upwardly and forwardly when the cigarette packages are to be placed in the machine.

From Fig. 5, it may also be seen that coiled springs 29 on the follower rod 24 are secured to the followers 25 for the purpose of urging the followers toward the bottoms of the cigarette boxes, and each spring preferably has one of its ends

secured to a follower, and its other end secured to the follower rod. From Fig. 5 it may be seen that the plates 22 are spaced from the walls 10 to accommodate chains 30, each of which has one of its ends secured to one of the ends of the rod 24, and its other end connected to a reel 31. There are two of these reels, and they are mounted on the end portions of a shaft 32 which is journaled in the walls 10, and this shaft is provided with a mutilated gear 33 that is fast on the shaft, and is actuated by the single tooth 34 of a mutilated gear 35 which is fixed to the shaft 28, as in Fig. 7.

Each time the shaft 28 makes a complete revolution, the tooth 34 will move the shaft 32 one step, and this will cause the chains 30 to move the followers 25 a distance equal to half the thickness of a cigarette, and consequently, the layers of cigarettes in the boxes will be fed forward step by step during the operation of the machine. When the boxes have been emptied, the tooth 34 will reach the untoothed portion 36 of the gear 33, and consequently, even if the machine is actuated, the followers will not be moved.

For guide purposes, the chains pass about pulleys 37a mounted on a rod 38a which connects walls 10.

The followers feed the cigarettes from the box on to a relatively narrow guide plate 38 which is arranged in an inclined position and has its ends secured to the walls 10 by any suitable means such as bolts 39.

In order to control the passage of the cigarettes from the plate 38, the machine is provided with a number of gates 40 and dump plates 41. As there are four rows of layers of cigarettes in two of the flat packages, the present machine has four gates 40 and four dump plates 41, and it will be understood that if the machine is to be used with a single package, only two gates and two dump plates would be used. However, if the machine was built for more than two packages, more than four gates and dump plates would be employed.

The gates are pivotally suspended from the shaft 38a, and the dump plates are pivotally mounted on a shaft 43. Each dump plate has a recess 44 to accommodate a single cigarette, and from Fig. 6 it will be noted that when the dump plate is in dumping position, the gate 40 is in such position as to prevent the following cigarettes from dropping down on to the delivery plate 45.

Pairs of fingers 46 and 47 are rigidly mounted on the shaft 28, and these fingers are at such angles to one another as to operate successively on the gates and dump plates. The fingers 46 actuate the gates, and to prevent them from operating the dump plates, each dump plate has a slot or notch 48 in its upper end.

The fingers 47 in their movement, strike the upper ends 49 of the dump plates, and move the same in a clock-wise direction.

Normally, the dump plates are held in contact with the guide plate 38 by means of springs 50, each having one of its ends connected to a dump plate and its other end connected to a cross bar 51.

When the machine is not in operation, the gates 40 rest against the dump plates.

From the foregoing it is believed it will be understood that the shaft 28 controls the operation of the machine, and it will be noted that this shaft has its end portions journaled in the walls 10, and one of its extremities is provided with a ratchet wheel 52 having four notches 53 to accord with the number of dump plates. A lever 54 is pivotally mounted on the shaft and carries a

pivotal pawl 55 which is urged toward the ratchet wheel by a spring 56. It will be understood that when the lever 54 is moved 90 degrees, it will actuate the shaft 28 one step in a counter-clock-wise direction, as seen in Fig. 4, and movement of the shaft in the opposite direction is prevented by a stop pawl 57, which is pivotally mounted at 58 on one of the walls 10, and is pulled toward the pawl by a spring 59.

The tail 60 of the lever extends through a slot 61 in a bracket 62 which is secured to a conventional coin operated mechanism 63. When there is no coin in the machine, actuation of the slide bar 64 of the coin control will move the bracket 62, but less than 90 degrees, so the machine will not operate unless a coin is placed in the same. When a coin is placed in the machine, and the slide bar 64 is pushed inwardly, the bracket 62 will shift the lever 54 ninety degrees, and consequently, the shaft 28 will be moved a quarter of a turn. This will cause one of the fingers 46 to push its associated gate 40 inwardly, and to cause any cigarettes which are engaging the gate to be pushed back on to the plate 38. During this quarter turn of the shaft 28, the other finger 47 of that particular pair of fingers will strike the upper end of the corresponding dump plate with the result that the parts will be moved from the position shown in Fig. 3, to the position shown in Fig. 6, and a single cigarette will be dropped on to the delivery plate 45.

Owing to the fact that the fingers are at different angles to one another, it will be understood that the gates and dump plates will be progressively actuated, and during a complete revolution of the shaft 28, a single cigarette will be fed from each row of cigarettes in the boxes. As the shaft 28 completes its rotation, the tooth 34 on the same will cooperate with the mechanism with which it is connected, to feed both followers forward the required distance to move a pair of cigarettes from the front end of each row on to the gravitating guide plate 38.

From the foregoing it is believed that the construction, operation and advantages of our vending machine may be readily understood, and it is manifest that changes may be made in the details disclosed, without departing from the spirit of the invention, as expressed in the claims.

What we claim and desire to secure by Letters Patent is:

1. A vending machine comprising a cigarette magazine, guiding means for receiving cigarettes fed from the magazine, a gate to prevent discharge of cigarettes from the machine, a dump plate cooperating with the gate for releasing a cigarette from the machine while the gate is closed, said gate and dump plate, while the machine is at rest, obstructing the release of cigarettes from the guiding means, and manually operated means common to the gate and dump plate and operatively connected to said gate and dump plate for successively actuating the gate and dump plate.

2. A vending machine comprising a relatively flat cigarette magazine having an imperforate bottom, and arranged at a slight inclination to the horizontal, a gate to prevent discharge of cigarettes from the machine, a dump plate cooperating with the gate for releasing a cigarette from the machine while the gate is closed, means for successively actuating the gate and dump plate, a guide plate positioned at the lower end of the magazine and sloping downwardly toward the opposite end of the magazine for guiding cigarettes

from the latter, and means for feeding the cigarettes from the magazine.

3. A vending machine comprising a cigarette magazine, and means for feeding cigarettes from the magazine, said feeding means including a rod, means for guiding the rod in a path parallel to the bottom of the magazine, a follower pivotally mounted on the rod and slidably along the bottom of the magazine, and resilient means for urging the follower toward the bottom of said magazine.

4. A vending machine comprising a cigarette magazine and means for feeding cigarettes from the magazine, said feeding means including slotted plates, a shaft guided by the slots of the plates in a path parallel to the bottom of the magazine, a follower mounted on the shaft and extending into said magazine, and resilient means for urging the follower toward the bottom of said magazine.

5. A vending machine comprising a cigarette magazine and means for feeding cigarettes from the magazine, said magazine having a substantially V-shaped bottom surface on which the cigarettes rest, said feeding means including plates arranged at the sides of the magazine and provided with V-shaped guide slots, a rod having its ends guided by said slots, means for moving said rod step by step along the slots, and a follower carried by the rod and extending into said magazine.

6. A vending machine comprising a cigarette magazine and means for feeding cigarettes from the magazine, said feeding means including plates arranged at the sides of the magazine and provided with V-shaped guide slots, a rod guided by said slots, a follower secured to the rod and extending into the magazine, a reel shaft, reels mounted on said shaft, chains having their ends connected to the reels and to said rod, a mutilated gear fixed to said shaft, and another mutilated gear for actuating the first mentioned gear.

7. A vending machine comprising a cigarette magazine and means for feeding cigarettes from the magazine, said magazine having an inclined guide plate at one end thereof to form with the bottom of the magazine a substantially V-shaped supporting surface, said feeding means including a follower extending into the magazine, and substantially V-shaped guides for the follower arranged approximately parallel to said supporting surface.

8. A vending machine comprising a magazine from which cigarettes are to be discharged, guiding means for receiving cigarettes fed from the magazine, a gate arranged transversely of the guiding means and engageable with the sides of the cigarettes to normally prevent discharge of cigarettes from the machine, a dump plate cooperating with the gate for releasing a cigarette from the machine while the gate is closed, said gate and dump plate obstructing the release of cigarettes from the guiding means while the machine is at rest, and means for successively actuating the gate and dump plate, said gate being pivotally suspended.

9. A vending machine comprising a magazine from which cigarettes are to be discharged, guiding means for receiving cigarettes fed from the magazine, a gate to prevent discharge of cigarettes from the machine, a dump plate cooperating with the gate for releasing a cigarette from the machine while the gate is closed, said gate and dump plate obstructing the release of cigarettes from the guiding means while the machine is at rest, and manually op-

erated means common to the gate and dump plate and operatively connected to said gate and dump plate for successively actuating the gate and dump plate, said dump plate having a recess to accommodate a single cigarette.

10. A vending machine comprising a magazine from which cigarettes are to be discharged, a gate to prevent discharge of cigarettes from the machine, a dump plate cooperating with the gate for releasing a cigarette from the machine while the gate is closed, and means for successively actuating the gate and dump plate, the last mentioned means including a shaft, and a pair of fingers on said shaft cooperating with the gate and dump plate to successively move the same.

11. A vending machine comprising a magazine from which cigarettes are to be discharged, a gate to prevent discharge of cigarettes from the machine, a dump plate cooperating with the gate for releasing a cigarette from the machine while the gate is closed, and means for successively actuating the gate and dump plate, the last mentioned means including a shaft, and a pair of fingers on said shaft cooperating with the gate and dump plate to successively move the same, the dump plate having a cut-away portion to permit one of the fingers to pass by the dump plate without actuating the latter.

12. A vending machine comprising a magazine from which cigarettes are to be discharged, gates to prevent discharge of cigarettes from the machine, dump plates cooperating with the gates for releasing cigarettes from the machine while the gates are closed, means for successively actuating the gates and dump plates, and a pivotally mounted vertically disposed divider extending into the box for maintaining the cigarettes in rows arranged side by side, each gate and its associated dump plate controlling the feed of cigarettes from one of the rows of cigarettes.

13. A vending machine comprising a magazine from which cigarettes are to be discharged, a gate to prevent the discharge of cigarettes from the machine, a dump plate cooperating with the gate for releasing a cigarette from the machine while the gate is closed, means for successively actuating the gate and dump plate, a guide plate positioned in one end of the magazine and sloping downwardly away from said end for guiding cigarettes from the magazine, and a narrow second guide plate positioned between said end of the magazine and the dump plate and oppositely inclined downwardly away from said end.

14. A coin controlled vending machine comprising a magazine from which cigarettes are to be discharged, a gate to prevent discharge of cigarettes from the machine, a dump plate cooperating with the gate for releasing a cigarette from the machine while the gate is closed, a manually operated means common to the gate and dump plate and operatively connected to said gate and dump plate for successively actuating the gate and dump plate, the last mentioned means including a shaft provided with a ratchet wheel, and a lever pivotally mounted on said shaft and provided with a pawl cooperating with the ratchet wheel, and means for actuating said lever.

15. In a vending machine a magazine from which cigarettes are to be discharged, an inclined guide plate, a plurality of pivotally mounted gates adapted to cooperate with the plate for preventing cigarettes from rolling off the same, a plurality of pivotally mounted dump plates against which the gates may abut, each dump plate having a cigarette receiving recess, and

- means for successively actuating first one of the gates and then one of the dump plates for holding cigarettes on the guide plate while a cigarette is dropped by the dump plate.
- 5 16. In a vending machine a magazine from which cigarettes are to be discharged, an inclined guide plate, a plurality of pivotally mounted gates adapted to cooperate with the plate for preventing cigarettes from rolling off the same,
- 10 a plurality of pivotally mounted dump plates against which the gates may abut, each dump plate having a cigarette receiving recess, means for successively actuating first one of the gates and then one of the dump plates for holding cigarettes on the guide plate while a cigarette is dropped by the dump plate, and springs for yieldingly holding the dump plates in closed position.
- 15 17. A vending machine comprising a magazine from which cigarettes are to be discharged, a gate for controlling the discharge of cigarettes from the magazine, a stationary delivery plate to receive cigarettes from the machine, a dump plate arranged above the delivery plate and cooperating with the gate for obstructing the release of a cigarette from the magazine while the gate is open, and manually operated means common to the gate and dump plate and operatively connected to said gate and dump plate for successively closing said gate and opening the dump plate to release a cigarette from the magazine on to said delivery plate.
- 20 18. A vending machine comprising a magazine from which cigarettes are to be discharged, a gate to prevent the discharge of cigarettes from the machine, guiding means for the cigarettes arranged between the magazine and gate, said gate extending transversely of the guiding means and engageable with the sides of the cigarettes, a dump plate cooperating with the gate for releasing a cigarette from the machine while the gate is closed, said gate and dump plate obstructing the passage of cigarettes from the guiding means, and means for successively actuating the gate and dump plate to cause the gate to move to a position over the guiding means and for causing the dump plate to drop a cigarette.
